UNITED STATES PATENT OFFICE.

LEE SHOWERS, OF CHARLEROI, PENNSYLVANIA, ASSIGNOR TO PITTSBURGH PLATE GLASS COMPANY, A CORPORATION OF PENNSYLVANIA.

POT SEAT.

Application filed October 6, 1921. Serial No. 505,896.

To all whom it may concern:

Be it known that I, LEE SHOWERS, a citizen of the United States, and a resident of Charleroi, in the county of Washington and State of Pennsylvania, have made a new and useful invention in Improvements in Pot Seats, of which the following is a specification.

The invention relates to pot seats for use in connection with the making of plate or optical glass in which the glass is melted in large clay pots which are placed in the furnace and exposed to the action of heat until the batch employed is reduced to a molten state and the glass fined. These pots are ordinarily placed directly upon the clay floor of the furnace, which floor is slightly crowned or arched. This crown renders it difficult to give the pot a flat seat and in the course of time the floor becomes uneven due to wear or settling of the ground beneath. As a result the pots sometimes crack or break due to the strains involved in the uneven support. The purpose of the present invention is the provisions of improved means whereby a perfectly flat even seat for the pot is secured, and whereby such seat may be readily replaced in case any unevenness develops or the seat becomes cracked or broken in service. Certain embodiments of the invention are illustrated in the accompanying drawings wherein:

Figure 1 is a vertical section through the improved pot seat construction with a pot in position thereon and Fig. 2 is a vertical section through a modified construction in which the upper seating block is omitted.

Referring to the drawings, 1 is a portion of the floor of the pot furnace, which furnace, as indicated, has a slight arch or crown. This floor is of clay and rests upon the ground or other suitable foundation 2. At those points at which the pots are to rest upon the floor circular sections of the floor are cut out and the seating sections 3 fitted in place. These seating sections are preferably made of clay of a tougher, more resistant composition than that of the floor 1 itself. These seating blocks 3 are dried and burned hard before positioning and they may be either positioned at the time the floor is laid, or in case the improvement is added to an old furnace, the floor must be cut away to receive the blocks. They pref-

erably project above the floor as illustrated, 55 although this is not necessarily the case.

Mounted upon the top of the block 3 is a second block 4 of refractory material such as pot clay but having a higher percentage of silica or other material tending to make 60 the block more refractory. This block 4 is preferably of a larger diameter than the block 3 beneath, so that any glass which drops from the block will not get under the stone, but will drop to the floor. This keeps 65 the upper block from sticking to the lower one. The lower part of the block 4 is cupped or recessed as indicated at 5 and the space is filled with a finely divided material, preferably carbonaceous in character, such as 70 coke breeze, the purpose being to secure for the block a more level seat and prevent adhesion or welding between the opposing surfaces.

The upper surface of the block 4 which is to receive the pot is preferably made perfectly flat so that it will contact with the pot throughout substantially the entire area thereof. The pot is thus supported very uniformly and without any undue strain 80 such as would ordinarily be the case in seating a pot upon a floor having a crown or arch or upon a floor section more or less worn or uneven. It is relatively easy to make the top surface of the block perfectly 85 flat and true, and in case any unevenness develops in use it is a simple matter to remove the block 4 and substitute another in its place, the block being preferably provided with the lugs 6 to facilitate gripping it 90 with a pair of tongs carried by an overhead crane. In order to prevent any adhesion or welding between the pot 7 and the upper surface of the block 4, the upper surface of the block 4 is preferably sprinkled with 95 a thin layer of coke breeze before the pot is placed in position.

Fig. 2 illustrates a modification in which the floor 2 is provided with a seating block 8, upon which the pot 9 rests directly, the 100 block corresponding to the block 4 of Fig. 1 being omitted. In this construction the upper face of the block 8 is made perfectly flat so as to give an even support to the pot. This construction lacks certain advantages 105 of the construction of Fig. 1, but does have the advantage over the old type of construction that the block 8 may be made of a ma-

terial more resistant to cracking than the floor and is less liable to crack than the floor because of the limited area which it covers. It also has the advantage that its 5 upper surface may be made perfectly plain and flat before the block is put in position, thus giving a better support for the bottom of the pot than the curved surface of the floor.

10. What I claim is:

1. In combination with the arched clay floor of a pot furnace having an opening therein, of a seating block of refractory material set in fixed position in said opening in the floor, the said block having a flat continuous upper surface adapted to engage and support substantially the entire bottom area of the pot.

2. In combination with the arched clay floor of a pot furnace having an opening therein, of a seating block of refractory material, more resistant to wear and strain than the material of the floor itself, set in fixed position in the opening in the floor 25 and having its upper surface flat and continuous and adapted to engage and support substantially the entire bottom area of the pot.

3. In combination with the floor of a pot 30 furnace, of a seating block of refractory material set into the floor, and a second block of refractory material mounted upon the top of the seating block and adapted to receive the pot.

35. 4. In combination with the floor of a pot furnace, of a seating block of refractory material set into the floor, and a second block of refractory material mounted upon the top of the seating block and adapted to 40 receive the pot, said second block having a flat upper surface.

45. 5. In combination with the crowned floor of a pot furnace, of a seating block of refractory material seated in the floor with its upper surface projecting above the floor,

and a second block of refractory material mounted upon the top of the seating block and adapted to receive the pot, said second block having a flat upper surface.

6. In combination with the floor of a pot 50 furnace, of a seating block of refractory material set into the floor, a second block of refractory material mounted upon the top of the seating block and adapted to receive the pot, and a layer of divided material between the surfaces of the blocks.

7. In combination with the floor of a pot furnace, of a seating block of refractory material set into the floor, a second block of refractory material mounted upon the top of the seating block and adapted to receive the pot, and a layer of divided material 60 between the surfaces of the blocks, one of said surfaces being capped or recessed to receive such divided material.

8. In combination with the floor of a pot furnace, of a seating block of refractory material set into the floor, a second block of refractory material mounted upon the top of the seating block and adapted to receive the pot, and a layer of divided material 70 between the surfaces of the blocks, the lower face of the second block being cupped or recessed to receive such divided material.

9. In combination with the floor of a pot furnace, of a seating block of refractory material set into the floor, and a second block of refractory material mounted upon the top of the seating block and adapted to 75 receive the pot, said second block projecting above the floor of the furnace, and being of less diameter than the seating block.

In testimony whereof I have hereunto 80 subscribed my name this 30th day of September, 1921.

LEE SHOWERS.
